UNITED STATES PATENT OFFICE

HENRY D. HOBSON, OF BROOKLYN, NEW YORK.

DESIGN FOR A PUZZLE BOARD OR CARD.

SPECIFICATION forming part of Design No. 28,773, dated May 31, 1898.

Application filed December 20, 1897. Serial No. 662,752. Term of patent 8½ years.

To all whom it may concern:

Be it known that I, HENRY D. HOBSON, a citizen of the United States, residing at Brooklyn, in the county of Kings and State of New York, have invented and produced a new and original Design for a Puzzle Board or Card, of which the following is a specification.

My new design for a puzzle board or card is shown in the accompanying drawings, in plan view in Figure 1 and in cross-section in Fig. 2.

The leading feature of my design consists of a central maze inclosed within a square and supplemental mazes located outside of the square, the lines of the square being interrupted to form a connection with the outside mazes. The center maze is provided with an

open space in the center thereof. This is also true of the lower maze, while the upper maze is completely filled with the series of lines constituting the maze. The central maze ²⁰ along its lower edge has a representation of mountains or hills.

I claim—

The design for a puzzle board or card, as herein shown and described. ²⁵

In testimony whereof I affix my signature in presence of two witnesses.

HENRY D. HOBSON.
